UNITED STATES PATENT OFFICE.

LÉON EMILE RÉMONDY, OF PARIS, FRANCE.

PERCUSSION FUSE.

Application filed July 5, 1927, Serial No. 203,612, and in France October 8, 1926.

Percussion fuses operating by driving in and, more particularly, fuses operating by driving in and inertia are known, such as those forming the subject of prior Patent No. 1,459,075. These fuses are extremely sensitive, that is to say they are adapted to operate as a result of impact with an obstacle offering a very small resistance, such as the wing fabric of an aeroplane, very soft soil, etc.

The present invention relates to a device which is adapted to be employed in combination with percussion fuses operating by driving in and more particularly with the type of fuse operating by driving in and inertia claimed in the above mentioned prior specification. This device while retaining the high degree of sensitiveness of the fuse and permitting it in particular to operate in very soft soil and even in water, on the other hand makes it impossible for it to operate upon impact with certain light obstacles. The device may be advantageously employed in all cases when the fuses are not employed for firing upon aircraft.

In practice the new device will prevent the untimely operation of very sensitive percussion fuses as the result of impact with light flexible obstacles accidentally encountered near the muzzle of the gun or along the path of the projectile, such as small branches or other light screens, made of fabric for example, which are employed for concealing the gun, the small branches of bushes, the stems of cereal crops encountered before the fall of the projectile, etc.

This device consists essentially in a perforated obturating cap or disc integral with the fuse body or mounted upon the latter; the orifices formed in the base of the cap or in the obturating disc being of sufficient dimensions to allow the free entry of soft or fluid material (ooze, soft earth, sand, water, etc.) but on the other hand making it impossible for branches, twigs or other similar obstacles which may be struck transversely to become engaged and have access to the percussion mechanism. The strength of the solid parts which separate the orifices from each other is nevertheless sufficiently small for the deformation of the end of the cap or of the obturating disc or its rupture to be obtained as the result of an impact against an obstacle offering resistance (hard

soil, stones, gravel, trunks of trees or main branches, etc.)

Various examples of construction of the invention are illustrated in the accompanying drawing.

Figures 1 and 2 show a first example in sectional elevation and in plan respectively.

The device, in this example, is assumed to be employed with a very sensitive percussion fuse operating by driving in and inertia, and comprising a casing A containing the whole of the firing mechanism (striker B integral or virtually integral with the casing, independent percussion cap C normally separated from the striker by a spacing spring D).

The protecting device is in this example formed by a perforated cap formed by an element E of the fuse body E-F. The extreme front part E of the fuse body is integral with a suitably perforated disc G. The orifices g bounded by the arms or solid parts g^1 are of dimensions such that they allow soft materials or fluids (soft earth, ooze, sand, water, etc.) to penetrate freely in order to have access to the movable carriage A-B-C.

On the other hand the disc, which is preferably slightly convex will ward off any light branch or other similar flexible obstacle, the stems of cereal crops, canvas screens, etc. which it may encounter during its travel, whether near the muzzle of the gun or while it is describing its trajectory.

On the other hand the strength of the said disc or cap end and particularly of the arms g^1 will be sufficiently small so that upon contact with a solid obstacle offering sufficient resistance, deformation or rupture will follow, the effect of which will be to cause the movable carriage to be driven into the projectile and the fuse to operate as a consequence.

The projecting device may, as shown in sectional elevation in Figure 3, be formed by a simple disc G—g the outer end of which is carried upon a shoulder e of the fuse body and is retained by turning down the outer edge of this fuse body at e^1 .

The protecting device may be constructed so as to be removable so that it may, as desired, be placed into position upon the projectile or removed therefrom according to the use to which the projectiles are to be put.

2
 The device may be formed, for example as shown in Figure 4, by a tapped socket G—g which is screwed upon a corresponding screwthread e² formed upon the end of the fuse body E. The socket G—g instead of being screwed on may be mounted by means of a bayonet joint or any other suitable securing or attachment means.

For storing and preservation the orifices 10 g may be closed by means of a thin light disc, of paper or fabric of extremely small strength which may remain attached to the cap during firing.

It is to be noted that the perforated protecting cap will prevent the accidental operation of the fuse of a projectile which happens to be fired from a gun from which the muzzle cover of leather or strong canvas has not been removed.

I claim—

A protecting device preventing the accidental operation of sensitive percussion fuses operating by driving it or by driving in and

inertia upon impact with obstacles accidentally encountered near the muzzle of the 25 gun or along the path of the projectile, such as branches or other screens serving to conceal the gun, the stems of cereal crops, the branches of shrubs, etc. consisting in a perforated cap or closing disc (G) integral with 30 the fuse body or mounted upon the latter, the orifices (g) formed in this cap permitting the free penetration of soft or fluid materials (ooze, soft earth, sand, water, etc.) 35 while preventing the engagement of light or flexible branches and twigs which are struck transversely, the strength of the solid parts (g¹) between the orifices (g) of the cap being on the other hand sufficiently weak for the deformation or rupture of the end 40 of the cap or of the closing disc to be effected upon impact with an obstacle offering some resistance.

In testimony whereof I have signed this specification.

LÉON EMILE RÉMONDY.
